1,925,057

STARTING MOTOR FOR INTERNAL COMBUSTION ENGINES

Frederick Price, Maud, Okla., assignor of one-half to George E. McKinnis, Jr., Shawnee, Okla.

Application May 8, 1929. Serial No. 361,369

2 Claims. (Cl. 60—16)

My invention relates in general to starting motors for internal combustion engines. It relates more in particular to a starter of the type employing a fluid such as compressed air.

5 In the commercial use of relatively large internal combustion engines, for example in the oil fields for operating drilling equipment, the use of electrical starters of the type generally employed with automobiles is entirely unsatisfactory. It 10 has been the custom under such conditions to start these motors by hand, or by means not adapted for full automatic performance. Now in locations such as pointed out there is usually an abundance of fluid under pressure such for example as compressed air, natural gas or the like. It is my purpose to employ such compressed fluid in the starting of internal combustion engines, and to this end I have designed an improved air 15 starter. I am aware that starters of this general character have been produced in the past, but none of such starters has been fully satisfactory nor would any of them suit my purpose.

Accordingly one of the principal objects of my invention is to produce an improved starter of this 20 type.

Another object is to utilize the compressed fluids of the character set forth for starting relatively large internal combustion engines.

Another object is the provision of a starter 25 which may be connected to any general type of motor, or which may be built as a part of any usual type of motor.

Another object is the provision of a starter which will automatically be rendered ineffective 30 when the internal combustion engine starts firing.

In accomplishing the objects of my invention I connect the starter to be driven in any suitable manner by an engine part, for example a timing shaft or cam shaft, the starter functioning to distribute the compressed fluid to the various cylinders in firing order so that the fluid operates the engine to be started, and is in turn operated by such engine to effect the proper timing. In the 35 system of valves employed to distribute the air

40 to the engine cylinders I avoid entirely the use of springs, poppets or other devices of this character which are readily thrown out of adjustment, and are expensive to manufacture.

Other objects and features of the invention will 45 appear from the following detailed description taken with the accompanying drawings wherein.

Fig. 1 is a conventional representation of an internal combustion engine, with the starter of my invention applied thereto;

50 Fig. 2 is a vertical sectional view through the

starter of my invention and showing the main details thereof;

Fig. 3 is a plan sectional view along the line 3—3 of Fig. 2, but with some of the parts shown in full lines better to show the relative positions, 60

Fig. 4 is a fragmentary vertical sectional view showing a preferred form of check valve as used in combination with my starter.

I refer first to Fig. 1 which illustrates a standard form of motor including the cylinder block 10, head 11, manifold 12 all supported by a suitable base 13. The motor is shown as a four cylinder one, and for the purpose of explaining my invention as will appear hereinafter the firing order may be assumed to be 1, 2, 4, 3.

The starter A may be connected in any suitable manner to a portion of the engine from which proper timing can be obtained and the starter distributes the compressed fluid from a suitable source (not shown) through pipes 16, 17, 18 and 19 to the cylinders above the piston heads and at the firing stroke of the piston. These pipes are arranged in a manner which will be brought out more fully hereinafter and each one is provided with a check valve mechanism B which will also be further described.

Now as to the starter proper this includes a main frame casting 21 and a shell casting 22, the shell forming a housing for a pair of gears 23 and 24 between which a driving connection is formed. The gear 24, being the driving gear, is keyed to a shaft 26, this shaft 26 being connected to be driven from the internal combustion engine. In actual installations with which I have had very good results I spline the shaft 26 to the cam motor timing shaft or cam shaft (not shown). The particular arrangement of the shell frame or casing 22 is such as used with this installation, and in this case an annular flange 27 is provided forming a part of the casing 22 and provided with holes 28 for receiving cap screws 29 (Fig. 1) which attach the starter to the internal combustion engine.

With reference now more fully to the parts of the starter the driven gear 23 is keyed to a main upright shaft 31 journaled in the main frame casting 21 by suitable bearings 32 and 33. At the top of the shaft a cam 34 is provided being held immovable with respect to the shaft by a key 36, and supported against longitudinal movement between nuts 37 and 38. The cam 34 (see Fig. 3) functions to operate the fluid controlling valves, and the construction of the valve system will now be pointed out.

The upper part of the main frame casting 21 is enlarged to form a head 39 and has a continuous outer annular chamber 41 through which openings 42 communicate to the outside. Three of these openings are closed with plugs 43—43 while the remaining opening is adapted to receive pressure reducer 44 to which a pipe 46 is connected, the pipe 46 leading to a suitable source of fluid pressure (not shown).

Within the head 39 and distributed around the inside of the annular passageway 41 are a plurality of separate openings 47, 48, 49 and 51 into which air under pressure is adapted to be admitted in successive order as determined by the operation of the valve mechanism. A hole is formed directly through the walls of each one of these chambers for the insertion of cylindrical liners 52—52, in which valve plungers 53—53 are adapted to reciprocate and uncover a series of ports 54—54 which interconnect the annular chamber 41 and the various smaller chambers indicated by the characters 47 to 51. By forming a connection between the chambers 47, etc. and the cylinders of the internal combustion engine air may be distributed to such cylinders in proper sequence to produce an operating effect. For bringing about this result openings 56—56 are provided communicating with the respective chambers and the head is provided with bosses 57—57 through which the openings 56 extend, the bosses being threaded for receiving the pipes 16 to 19 in proper order. Now with specific reference to the construction of the plungers 52, they include (Fig. 2) a plunger head 58 provided with packing rings 59 which are supported on the head by a follower 61, the follower 61 being secured to the head by a cap screw 62.

While with the starter properly adjusted no pressure fluid comes in contact with the center portion thereof, such center portion which is constructed open is provided with a plate 63, the plate being held in position by lugs 64 which are supported by machine screws 66 which extend into the body of the casting. Actually these screws extend into the web portion which separates the chambers 47, 48, etc. The main function of the plate 63 is to prevent the entrance of dirt into the starter, and to serve for the introduction of a lubricant which is brought therethrough by a pipe 67 suitably threaded into a boss provided in the center of the plate 63. By means of the oil introduced at this point the entire associated mechanism is continuously lubricated. Whatever lubricant might possibly escape past the plungers and be blown into the engine cylinder can have no deleterious effect on the operation thereof.

A positive drive being obtained from the internal combustion engine to the distributor portion of the starter, when the starter is properly timed with the engine it will remain so timed. For setting the timer the main frame casting 21 is rotatable on the shell casting 22 and may be turned with respect thereto to effect proper timing. Set screws 69—69 are provided for preventing relative turning of these two portions of the frame after they have been set.

Turning to Fig. 4 I show therein a portion of the top of a cylinder 71 in which a piston 72 is reciprocable. The cylinder head is provided with a passageway 73 threaded at the top to receive the check valve B of my invention. This mechanism is shown in the form of an L but it may of course have other forms. It includes a main frame portion comprising a straight piece

74 and an L 76, a threaded connection being provided between these two members for assembling purposes. A seat insert 77 is included in the assembly and is held by the annular flange 78 formed on the inside of the L 76, and the end of the member 74. This seat insert is provided with a standard type of annular seat for receiving a poppet type of valve 79. The stem 79a is slidable in an annular centrally disposed opening in a web portion 77a of the member 77. This web has a series of openings 77b for the passage of the fluid under pressure. A spring 81 surrounds the valve stem 79a and bears against the web 77a at one end and a retaining washer 82 at the other end, this retaining washer being held in position in any suitable manner, in the present case by a pin 83. The lower end of the member 74 is narrowed to form a shank 80 which is threaded for insertion into the opening 73 whereby the entire assembly is connected to the head of the cylinder.

Very great economy and simplicity is found in the manufacture and use of my invention over all other forms of starters of this general type with which I am familiar. It is preferably driven directly off of the motor cam shaft which in a four cycle engine rotates at half the speed of the crank shaft and so a direct drive therefrom operates the distributor to effect a proper number of impulses in accordance with the engine firing. In other words at each firing stroke of each piston a blast of compressed fluid is projected against the top of the piston and drives the same downwardly in the same way that an ignited charge would affect it. When the compressed fluid is admitted to the starter the distributor is also in a position to supply pressure to a cylinder which is on the down stroke, so that all that is necessary is simply to admit the pressure air and the starter operates. While any sort of valve may be employed for this purpose I show a hand operated valve 84 (Fig. 1). The source of supply of the fluid pressure is not of prime importance in the present invention.

The construction of the distributor head will be readily understood to be of great practical value in that the parts are very quickly changed or adjusted as might be necessary under various circumstances. To begin with to remove the entire distributor it is simply necessary to loosen the set screws 69 and pull the entire distributor upwardly. This of course assumes proper disposition of the piping before hand. If one of the plungers is not operating properly it is simply necessary to remove the adjacent plug 43, withdraw the plungers bodily, withdraw the liner 52 if necessary and replace with new parts. If an entirely new change is not necessary any portion may be repaired or adjusted, as for instance new packing rings can readily be applied to the plungers. If the cam 34 is not operating smoothly the plate 63 can be removed, the nut 38 taken off, and the cam readily replaced with a new cam without requiring a dismantling of any other portion of the starter.

In the arrangement of the check valves the spring 81 is regulated to have such tension as may be required in the proper operation of the poppet valve 79. The starting pressure which I employ is generally in the neighborhood of 100 to 150 pounds pressure and the pressure in the cylinder on firing is found greatly to exceed this pressure so that the valve will automatically be maintained in a closed position due to this unequal and offsetting pressure. This renders the starting fluid

automatically ineffective. After air has been admitted to force a given piston downwardly and the source of pressure cut off from direct connection with such piston, a built up pressure of some magnitude will remain in the communicating pipe. In the subsequent operation of the piston, particularly on the suction stroke (assuming the existence of a four cycle engine) there will be a tendency for the valve 79 to be forced open by such residual pressure. Now I construct the spring 81 of such strength as to overcome this pressure so that the valve will be open at no time except when full starting pressure for which the device is designed is applied against the valve.

I have shown a specific embodiment of my invention and described such embodiment in detail so that those skilled in the art may readily understand the manufacture and operation thereof. I do not wish to restrict myself, however, to the particular features shown and described, the invention being limited only by the scope of the appended claims.

What I claim as new and desire to protect by United States Letters Patent of the United States is:

1. An engine starting mechanism for the pur-

pose described including a main frame casting, and an outer shell casting disposed partially around the main frame casting, means on the shell casting for securing the same to an engine block, a shaft disposed in the shell casting and adapted for connection to an engine shaft, a centrally disposed shaft journaled in the main frame casting, a gear connection between the two shafts for driving said centrally disposed shaft, a fluid distributor mechanism carried by the main frame casting, and means for adjusting and maintaining the relative positions of the shell casting and main frame casting for timing the distributor with reference to the engine.

2. An engine starting mechanism as set forth in claim 1 wherein the distributor includes a main pressure chamber communicating with a source of fluid pressure, a plurality of pressure receiving chambers one for each engine cylinder, a series of ports between the pressure receiving chamber, plungers normally serving to close said ports and means for moving the plungers to uncover the ports to the pressure receiving chambers in accordance with the timing of the engine.
